MUTE FOR A TROMBONE

Samuel Thomas Beversdorf, Bloomington, Ind., assignor to Robert W. Wachtel, doing business as Wachtel Music
Products, Columbus, Ohio

Filed Mar. 26, 1973, Ser. No. 344,938

Term of patent 14 years

Int. Cl. D17—02

U.S. Cl. D56—1 C

FIG. 1 is a perspective view of a mute for a trombone showing my new design, the opposite side being identical to that shown.

FIG. 2 is a fragmentary sectional view taken along line 2—2 of FIG. 1.

FIG. 3 is a plan view taken along line 3—3 of FIG. 1.
I claim:

The ornamental design for a mute for a trombone, as shown and described.
